GAUGING APPARATUS

William J. Fedorchak, Granite City, Ill., assignor to
Owens-Illinois Glass Company, a corporation of Ohio

Application August 26, 1955, Serial No. 530,821

4 Claims. (Cl. 214—340)

The present invention relates to gauging apparatus of the type presently utilized in the detection of seams, ridges and such irregularities in glass bottles, jars and the like articles. Examples of the type of apparatus to which my invention particularly relates and in which it may to advantage be incorporated, are disclosed and claimed in my Patents Nos. 2,327,629 issued August 24, 1943 titled Gauging Machines and 2,355,719 issued August 15, 1944 titled Gauging and Seam-Detecting Apparatus.

In the patented machine, the jar supporting pad which moves the jar vertically into and out of engagement with the centering and holding chuck at the open end of the jar, rotates continuously with the result that considerable time consuming care must be exercised in placing jars or such articles on the pad to the end that they will not be thrown to one side by centrifugal force. Such of necessity results in low productive speed.

An object of my invention is to overcome the above objections and others and to this end I provide mechanism whereby the jar, or such article, may with ease be properly positioned and securely held between the supporting pad and centering chuck, prior to initiation of any rotative movement of the pad.

A further object of my invention is the provision of an apparatus of the above character in which the step of final gripping of the article between the pad and chuck automatically initiates rotation of the pad and article and through the latter also rotates the chuck at the open end of the article.

Another object of my invention is the provision of braking means which functions automatically, incident to initiation of the article removing operation, to quickly bring the pad to a standstill.

It is also an object of my invention to provide, in apparatus of the above character, pad driving means including a readily replaceable driving ring which is intended for engagement with the lower side of the article supporting pad incident to upward axial movement of said ring approximately at the time of completion of the article chucking operation.

Other objects will be in part apparent and in part pointed out hereinafter.

In the drawings:

Fig. 1 is a fragmentary side elevational view with parts in section showing my invention incorporated in a machine such as that illustrated in either of the above identified patents.

Fig. 2 is an enlarged fragmentary vertical sectional view with parts in elevation of my invention.

Fig. 3 is a detail sectional elevational view showing the construction of the pad, brake disk and connections therebetween.

The herein disclosed apparatus is intended for use in gauging round articles, such as glass jars, and includes a platform 10 supporting gauging mechanism 11, said

2

platform mounted upon posts 12 which extend downwardly to a base (not shown). A generally conical chuck, or centering cone 13 is rotatably mounted upon and depends from the platform 10 in proximity to the gauging mechanism 11, and, as will be apparent presently, functions to air in the proper positioning and retention of the jar 14 upon the rotatable supporting pad 15. This pad 15 is carried by a horizontal bracket 16 which is movable vertically for the purpose of bringing the container 14 into firm engagement with the chuck 13 and for the additional purpose of setting in motion the specific mechanism which rotates said pad 15. The foregoing mechanism and details of same are disclosed in my patents above identified.

As is explained above, the pad 15 rotates only after a jar or the like article has been placed thereupon and the bracket 16 elevated sufficiently to bring the upper end of the jar into engagement with the chuck 13 and through a continuation of such upward movement of the bracket a short distance beyond that which is necessary to chuck the container, effecting operative engagement between said pad 15 and a continuously moving driver 17. Thus, the pad is at a standstill at the time the jar or other container is placed thereon and remains so until the container has been securely gripped between the pad 15 and the chuck 13. Such functioning of the present invention is possible by reason of the particular mechanism which is carried by the bracket 16.

This bracket includes a base portion 18 and upstanding marginal flange 19 and a top cover 20 which is separably attached to said flange 19. The bottom 18 is provided with a vertical axial opening 21 which is in register with a vertical opening 22 in the aforementioned cover 20. An annular thickened portion provides a collar 23 defining the opening 21 in the bottom 18. A ball-bearing 24 is mounted within the collar 23, being supported therein by an inwardly directed flange 25 at the lower end of the collar 23. A continuously rotating spur gear 26 is positioned within the bracket 16 and runs in mesh with a driving pinion 27. A hub 28, carried by the spur gear 26 is fitted into the aforementioned ball-bearing 24. The lower end of this hub 28 may, as shown, lie substantially flush with the lower end of the ball-bearing 24 while its upper end extends a short distance above the web portion of the spur gear and projects into an annular driving collar 29, the latter being secured to the spur gear by one or more countersunk screws 30 or similar fasteners. The spur gear 26 and driving collar 29 together comprise the continuously operating driving means which at intervals is brought into frictional driving engagement with the lower side of the jar supporting pad 15.

The pad 15 (Fig. 3) is provided with a depending axial stub-shaft 31 which extends axially downward into the hub 28 of the spur gear 26, being spaced from said hub by a sleeve 32. The lower end of this stub-shaft 31 has a screw threaded connection to the diametrically reduced upper end portion 33 of a lifter rod 34, the latter being positioned in close proximity to the upper end of a rod 35. These rods, Fig. 2, are disposed in vertical and axial alignment and the lower rod 35 rises from a carrier 36 which is suitably mounted in a holder 37, such holder being separably connected to the aforementioned bottom 18 of the bracket 16 by means of attaching screws 38. This holder 37 includes a horizontal flange portion 39 which is spaced downwardly from the adjacent end of the collar 23 to accommodate a brake-disk 40. This brake-disk 40 includes an axial annular hub portion 41 which encircles the reduced upper portion of the lifter rod 34, Fig. 3, and together

with the carrier 36 confines a coil spring 42 which encircles the adjacent end portions of the lifter rods 34 and 35 and normally serves to yieldingly hold the supporting pad 15 and brake-disk 40 in their uppermost positions, as best shown in Fig. 2. The spaced relationship between the lower side of the supporting pad 15 and the upper surface of the brake-disk 40 is slightly greater than the distance between the upper surface of the driving collar 29 and the lower end of the annular collar 23 of the bracket 16 with the result that normally the brake-disk 40 is yieldingly, but firmly frictionally held against the lower end of the collar 23, while the pad 15 is completely out of contact with the driving collar 29. Thus, normally the pad 15 is not rotating.

In operation, and assuming that the bracket 16 is in its lowermost position with the driving collar 29 rotating continuously, the operator will place a jar upon the supporting pad 15. The bracket 16 then is elevated so that the upper end of the jar is fitted over the conical chuck and incidentally centered by the latter, in the event the jar has not already been properly positioned in this respect. At this point, the jar is securely held and may be rotated rapidly about its axis without any likelihood of it being thrown out of the supporting pad 15 incident to rotation of the latter. The bracket 16 continues to move upwardly a very slight distance sufficiently to frictionally interengage the driving collar 29 and pad 15, with the result that the pad 15 very quickly begins to rotate and cause movement of the upper end of the jar relative to the gauging mechanism 11. Upon completion of the gauging operation, the bracket is lowered with the result that the driving connection between the collar 29 and pad 15 is completely broken and the brake-disk 40 performs its function prior to complete separation of the jar from the chuck 13. Thus, the pad and jar are brought to a complete standstill before the jar has been lowered sufficiently to lose the benefit of the holding function of the chuck. As is obvious, the likelihood of damage to glassware and loss of same by reason of its being thrown by centrifugal force from the supporting pad is practically negligible.

Modifications may be resorted to within the spirit and scope of the appended claims.

I claim:

1. In apparatus of the character described, a chuck, a bracket spaced below said chuck, a continuously rotating ring-like driver carried by said bracket, an article supporting pad coaxial with the driver and chuck and normally spaced upwardly out of contact with the driver, a coil expansion spring normally holding the driver and pad spaced apart, said bracket, being movable vertically upward toward the chuck a distance slightly more than is necessary to bring the upper end of an article resting upon the pad into contact with said chuck, whereby to

compress the spring and effect operative engagement between the pad and driver and thereby rotate the article.

2. The combination defined in claim 1 and brake means for stopping rotation of the pad comprising a disk positioned below the driver and coaxial with and rotating with the supporting pad and a stationary brake member on the bracket with which said disk is brought into frictional contact by separation of the driver and supporting pad.

3. In combination, a chuck, a bracket spaced below the chuck, a driver carried by the bracket, a rotatable article supporting pad carried by said bracket and disposed between and coaxial with the driver and chuck, spring means normally holding the driver and pad spaced apart axially, said bracket being movable vertically upward toward the chuck a distance greater than is necessary to bring an article resting upon the pad into contact with the chuck, whereby to interengage the driver and pad in opposition to the spring means and thereby effect rotation of the pad and article supported thereon, and braking means effective to stop rotation of the pad and article incident to separation of the driver and pad comprising a disc rotatable as a unit with said pad and movable axially upward a distance equal to the extent of separation of the driver and pad into frictional holding engagement with a non-rotatable part of the bracket under the influence of said spring means.

4. In apparatus of the character described, a vertically movable bracket, a centering chuck positioned above and spaced from the bracket, said bracket having a vertical opening therethrough positioned coaxially with said chuck, an article supporting pad arranged above and coaxial with said opening in the bracket, a depending stub-shaft fixed to the pad and extending through said opening, a brake disk encircling a lower portion of said shaft, spring means normally yieldingly urging the brake disk into a position for frictional gripping contact with a non-rotating part of the bracket, and a continuously rotating driver encircling said shaft and mounted within the bracket, said driver including a collar positioned with an upper surface in close proximity to the lower side of the article supporting pad, the spaced relationship between the lower side of the article supporting pad and the upper surface of the braking disc being such that lowering of the supporting pad a predetermined distance in opposition to the spring means said lower surface of the pad into driving contact with the upper face of the driver and disengages the braking disk from said non-rotating part of the bracket.
